ELASTIC BODY BELT

John W. Stafford, Chicago, Ill.

Application December 2, 1932, Serial No. 645,452

10 Claims.

(Cl. 241—8)

This invention relates to an improvement in elastic body belts, and particularly to an improvement in belts in which the elastic quality is supplied by a resilient device associated with the buckle.

A belt of this character not only permits greater freedom of movement of the body of the wearer, and consequently greater comfort, but due to the constant elastic pressure exerted on the clothing of the wearer, the garments are more firmly and securely held in position and prevented from working up or down, as so commonly results when non-stretchable belts are worn.

One of the objects of the present invention is the provision in a belt of this character of means whereby the belt may be more readily adjusted about the person of the wearer yet will be prevented from becoming released accidentally.

Another object of the invention is the provision of means whereby the device which provides the resilience of the belt may be readily attached to, removed from or exchanged for other similar devices without altering the belt proper.

One of the features of the invention resides in the provision of a slideable spring supporting bar and means associated therewith, whereby it may be readily joined to or separated from the bar of the buckle.

Another feature of the invention is the provision of the double portion of the belt between the separate layers of which means are provided whereby the spring and spring supporting bar may be removed readily from the belt without change of the belt structure.

Another feature of the invention is the provision of the spring abutment through which the spring supporting bar slides and means associated therewith for retaining the adjacent end of the spring out of the sliding contact with the spring supporting bar.

Other features and advantages will appear from time to time as the description of the invention progresses.

In the present disclosure the invention has been shown particularly applied to a military "Sam Browne" belt. It is to be understood, however, that with slight modification the invention may be readily adapted for use with belts of the ordinary commercial type.

It is believed the further disclosure of the invention will be understood most readily from a detailed description thereof taken in connection with the accompanying drawing, in which,

Fig. 1 is a view of one end of the belt with part removed to show the resilient means and buckle attached thereto;

Fig. 2 is a view of the spring supporting bar, spring, spring abutment and buckle engaging hook or clasp, detached from the belt;

Fig. 3 is an edge view of a portion of the spring supporting bar and spring showing the abutment stud carried by the bar;

Fig. 4 is a view of the buckle end of the belt showing the parts opened in position to receive the spring and parts associated therewith;

Fig. 5 is a view of the buckle end of the belt but with the buckle removed from the buckle engaging hook or clasp at the end of the spring supporting bar;

Fig. 6 is a view showing the buckle on the belt; and

Fig. 7 is a similar view of a "Sam Browne" belt and buckle.

Referring now to the drawing in which like reference characters indicate the same parts in the several views;

10 indicates the belt which may be formed of leather, fabric or any suitable material. One end of the belt is returned or bent back upon itself to provide an overlapping portion 11, which is shown in Fig. 4. Within the bight where the parts 10 and 11 join is the spring abutment 12, provided with an opening through which extends 25 the spring supporting bar or draw-member 13.

Positioned on the bar 13 and in sliding relation thereto is a rectangular or flattened coil spring 14. The spring 14 at one end abuts against the member 12, the end 15 of the wire being positioned on the returned flange 16 of the abutment 12.

By the provision of this arrangement, the end 15 of the wire may be caused snugly to contact the flange 16 so as not to engage and dig into the belt member and yet not scrape on the spring supporting bar 13, thus avoiding the squeaking sound often times produced by the end of the spring grating on the spring bar.

At 17 is shown a buckle having the tongues 18 carried on the bar 19. The spring supporting bar 13, beyond the juncture of the strap portions 10 and 11, has a laterally extended portion indicated at 20 which is formed to provide the returned or hook portions 21 arranged to receive the bar 19 of the buckle 17 as shown in 30 Fig. 1.

Spring supporting bar 13, adjacent its end remote from the hooks 21, is provided with a key hole slot 22. A stud 23 is formed with a reduced portion 24 arranged to pass through the 35

enlarged portion of slot 22. The reduced portion 24 is slightly grooved on the opposite sides thereof so that when it is moved to the reduced portion of slot 22 the edges of said slot enter the 5 grooves in the opposite sides of portion 24 and the stud is thus held firmly in position. Stud 23 acts as an abutment for one end of the spring 14 and the spring tends to retain the stud in the reduced portion of slot 22.

10 The portion 10 of the belt is provided with a slot 25 arranged to receive the upwardly extending portion of stud 23 and permit its movement therein longitudinally of the belt when the spring 14 is compressed by tension on the belt.

15 The portion 11 of the belt may conveniently be secured to part 10 by fastening devices 26 which may be similar to the ordinary glove fastener.

20 At 27 is shown a guard or shield, preferably of leather, which lies back of the belt buckle and is secured to part 10 by means of stitching 28. A snap fastener 29 may be provided to secure the free end of the part 27 to the part 11.

25 The end of the belt remote from the resilient device will be provided with a series of pairs of holes 30 arranged to receive the tongues 18 of the belt buckle. The belt is also provided with a series of button hole slots 31 adapted to receive the stud 23.

30 It has been found desirable to form the abutment 16 by folding a piece of sheet metal back on itself so as to provide slightly spaced parts between which the bar 13 may slide. The portions 32 of the abutment 16, on the opposite 35 sides thereof are preferably curved or rounded slightly outwardly so as to provide free clearance and also a definite abutment for the end 15 of the spring.

From the above description of the detailed 40 construction of the belt and resilient device therefor, it will be obvious that when the belt is buckled upon a wearer and the body of the wearer expands due to some exertion or movement, that the bar 13 will be drawn to the left 45 as seen in the several views compressing the spring 14, the end of the belt sliding loosely thru the loop 33. When the stress which has expanded the belt is removed the spring 14 will act to again return the belt parts to their normal position. 50 During this expansion and contraction the stud 23 will move forward and back in the slot 25 of the part 10 of the belt. The engagement of the stud 23 in one of the openings 31 of the belt as shown more particularly in Fig. 7 acts to more 55 definitely retain the belt parts in alignment as is necessary with the "Sam Browne" belt such as here disclosed.

With the detachable clasp or hook arrangement herein disclosed it is practically impossible 60 for the bar of the belt to become disengaged from the hooks 21 due to the fact that the middle one of the said hooks so nearly approaches the joining ends of the belt parts 10 and 11. When it is desired to unhook the belt, that is, remove the 65 buckle bar from the hooks 21, the bar 13 is drawn slightly outwardly against the resiliency of spring 14 the thumb or other part of the wearer is then placed against stud 23 to retain the spring under 70 compression. The buckle bar 19 may now be readily removed from the hooks and the meeting ends of the belt disengaged. Due to the peculiar construction of the clasp or hook 21 it is found that the bar may be replaced within the 75 hooks 21 without displacing the stud 23 altho the reverse of the process for disengaging the bar

may be employed in returning it to position if desired.

Due to the fact that the stud 23 is readily removable from the slot 22 the parts of the resiliency providing means may readily be removed either for replacement of the spring or repair or cleaning of any of the parts. All that is necessary in order to remove the parts is to force the stud 23 slightly to the left until it enters the enlarged portion of slot 22 whereupon it may 10 be readily removed from the bar 13. The bar 13 may be moved freely to the left and the spring 14 and abutment 16 taken out. In reassembling obviously just the reverse of this process would be followed.

15 While in the accompanying drawing the invention has been shown as applied to the "Sam Browne" belt, it is obvious that it may readily be applied to other belts or that many changes may be made in the details of construction without departing from the spirit of the invention. The invention should, therefore, be limited only by the scope of the appended claims.

Having thus described my invention, what I claim is new and desire to secure by United States Letters Patent is:

I claim:

1. In an elastic body belt, a strap folded back on itself at one end thereof to provide two layers of material, a bar having a portion thereof slidably mounted between said layers, a spring abutment within the bight of said layers, a coil spring positioned about said bar, one end of said spring engaging said abutment, a stud at the other end of said bar for retaining said spring thereon, said bar having a slot therein adjacent to the end thereof for receiving an end of said stud, a buckle and means for detachably joining the end of said bar to said buckle.

2. In an elastic body belt, a strap folded back 40 on itself at one end thereof to provide two layers of material, a bar having a portion thereof slidably mounted between said layers, a spring abutment within the bight of said layers, a coil spring positioned about said bar, one end of said spring 45 engaging said abutment, spring retaining means detachably secured to said bar remote from said abutment for retaining said spring thereon, said spring acting to hold said retaining means in position, a buckle, a cross bar on said buckle and 50 a hook at the end of said first mentioned bar for detachably engaging said cross bar.

3. In an elastic body belt, a strap, an overlying portion at the end thereof providing two layers of material, a bar having a portion thereof slidably mounted between said layers, a spring abutment between said layers at the end thereof, a coil spring about said bar, one end of said spring 55 engaging said abutment, a slot in said bar adjacent the end thereof, a spring retaining means in said 60 slot for retaining said spring thereon, a buckle, means for joining the end of said bar to said buckle, and means for detachably securing said layers together adjacent to the end of said bar and spring.

4. In an elastic body belt, a strap rebent on itself to provide two layers of material, a bar 70 slidably mounted between said layers, a spring about said bar, a spring abutment about said bar within the bight of said strap, means on the projecting end of said bar for removably engaging the bar of a buckle, and a stud removably secured to said bar adjacent to the end thereof remote from said buckle engaging means, said stud forming an abutment for one end of said spring, 75

- said spring acting to retain said stud in position.
5. In an elastic body belt, a strap rebent on itself to provide two layers of material, a bar slidably mounted between said layers, a spring about said bar, a spring abutment about said bar within the bight of said strap, means on the projecting end of said bar for removably engaging the bar of a buckle, and a stud removably secured to said bar adjacent to the end thereof remote from said buckle engaging means for retaining said spring on said bar, said spring acting to resist removal of said stud from said bar.
10. In an elastic body belt, a strap rebent on itself to provide two layers of material, a bar slidably mounted between said layers, a spring about said bar, a spring abutment about said bar within the bight of said strap, means on the projecting end of said bar for removably engaging the bar of a buckle, and a stud secured to said bar adjacent to the end thereof remote from said buckle engaging means, said stud forming an abutment for one end of said spring, one of said layers of said strap being provided with a slot to receive a portion of said stud.
15. In an elastic body belt, a strap rebent on itself to provide two layers of material, a bar slidably mounted between said layers, a spring about said bar, a spring abutment about said bar within the bight of said strap, said bar being provided with a key hole slot, and a stud having a portion adapted to pass through the large portion of said slot and be firmly seated in the reduced portion of said slot, said stud forming an abutment for one end of said spring.
20. In an elastic body belt, a strap rebent on itself to provide two layers of material, a bar slidably mounted between said layers, a spring about said bar, a spring abutment about said bar within the bight of said strap, said bar being provided with a key hole slot, and a stud having a portion adapted to pass through the large portion of said slot and be firmly seated in the reduced portion of said slot, said stud forming an abutment for one end of said spring.
25. In an elastic body belt, a strap rebent on itself to provide two layers of material, a bar slidably mounted between said layers, a spring about said bar, a spring abutment about said bar within the bight of said strap, said bar being provided with a key hole slot, and a stud having a portion adapted to pass through the large portion of said slot and be firmly seated in the reduced portion of said slot, said stud forming an abutment for one end of said spring.
30. In an elastic body belt, a strap rebent on itself to provide two layers of material, a bar slidably mounted between said layers, a spring about said bar, a spring abutment about said bar within the bight of said strap, said bar being provided with a key hole slot, and a stud having a portion adapted to pass through the large portion of said slot and be firmly seated in the reduced portion of said slot, said stud forming an abutment for one end of said spring.
35. In an elastic body belt, a strap rebent on itself to provide two layers of material, a bar slidably mounted between said layers, a spring about said bar, a spring abutment about said bar within the bight of said strap, said bar being provided with a key hole slot, and a stud having a portion adapted to pass through the large portion of said slot and be firmly seated in the reduced portion of said slot, said stud forming an abutment for one end of said spring.
40. In an elastic body belt, a strap rebent on itself to provide two layers of material, a bar slidably mounted between said layers, a spring about said bar, a spring abutment about said bar within the bight of said strap, said bar being provided with a key hole slot, and a stud having a portion adapted to pass through the large portion of said slot and be firmly seated in the reduced portion of said slot, said stud forming an abutment for one end of said spring.

portion adapted to pass through the large portion of said slot and be firmly seated in the reduced portion of said slot, said stud forming an abutment for one end of said spring, one of said layers of said strap being provided with a slot to receive a portion of said stud.

9. In an elastic body belt, a strap rebent on itself to form a bight at one end thereof and two layers of material, a spring abutment within said bight, a flat bar slidably mounted between said layers and extending through said abutment and bight, said abutment having an elongated slot therein thru which said bar passes, a substantially flat coil type spring in close engagement about said bar, one end of said spring being in engagement with said abutment, means at the opposite end of said bar for confining the spring thereon, said abutment being rebent on itself and the free end of the spring being in engagement with a side of said abutment remote from said bar, a buckle and means for detachably securing the end of said bar to said buckle.

10. In an elastic body belt, a strap rebent on itself to form a bight at one end thereof and two layers of material, a spring abutment within said bight, a draw-member slidably mounted between said layers and extending through said abutment and bight, said abutment having an elongated slot therein thru which said draw-member passes, a substantially flat coil type spring in close engagement about said draw-member, one end of said spring being in engagement with said abutment, means at the opposite end of said draw-member for confining the spring thereon, said abutment being rebent on itself and the free end of the spring being in engagement with a side of said abutment remote from said draw-member, a buckle and means for securing the end of said draw-member to said buckle.

JOHN W. STAFFORD.
